United States Patent Office

Des. 202,260
Patented Sept. 14, 1965

202,260

COMMERCIAL BUILDING

Leo Vincent McConologue, 1345 100th Ave.,
Oakland, Calif.

Filed Aug. 21, 1964, Ser. No. 81,398

Term of patent 14 years

(Cl. D13—1)

Fig. 1

Fig. 2

Fig. 3Fig. 4

FIGURE 1 is a top perspective view taken from the top and one side of a commercial building showing my new design;

FIGURE 2 is a rear elevational view thereof;

FIGURE 3 is a top plan view thereof;

FIGURE 4 is a front elevational view thereof.

I claim:

The ornamental design for a commercial building, substantially as shown.
